UNITED STATES PATENT OFFICE.

WILLIAM L. CHAMBERS, OF PLEASANT UNITY, PENNSYLVANIA.

CAR-BRAKE.

SPECIFICATION forming part of Letters Patent No. 249,302, dated November 8, 1881.

Application filed August 6, 1881. (No model.)

To all whom it may concern:

Be it known that I, WM. LATTA CHAMBERS, of Pleasant Unity, in the county of Westmoreland and State of Pennsylvania, have invented 5 a new and Improved Car-Brake; and I do hereby declare that the following is a full, clear, and exact description of the same, reference being had to the accompanying drawings, forming part of this specification, in which—

10 Figure 1 is a side elevation; Fig. 2, an inverted plan view, and Fig. 3 is a vertical cross-section through the line $x x$ of Figs. 1 and 2.

15 My invention relates to certain improvements in car-brakes of that form in which the brakes, instead of being applied to the wheels, are applied directly to the rails; and my improvement consists in the peculiar construction and arrangement of the said brakes, and in the peculiar construction and arrangement 20 of a bellows for applying the brakes by means of compressed air, as hereinafter more fully described.

25 In the drawings, A represents the body of a car each of whose trucks is equipped with my improved brake.

30 B is the truck-frame, in which are arranged, on each side, two vertical guides, $a a$, between which moves the vertical slide b , which rests in the plane of the car-wheels, and carries at 35 its lower end the brake-shoe c , which is curved up at its ends. These slides b are held in their vertical movement between the guides $a a$ by a tongued-and-grooved connection with the guides, so that they cannot get displaced or 40 out of their proper position. The brake-shoes c rest immediately above the rails, and have on their lower sides facing-strips d , of steel or hardened metal, which are made detachable from the shoes, so as to be readily removed 45 when worn or broken and another one substituted. For securing these hard facings to the shoe they are bent up around the ends of the shoe and fastened thereto by screws or bolts, as shown.

45 For depressing the brake-shoes of each truck and bringing them simultaneously against the track the tops of each slide b of the truck are connected by a horizontal bar, E, extending across the truck, which bar is loosely connected 50 to one end of an elbow-lever, C, which is fulcrumed in a bearing attached to the main cross-bar of the truck, and the vertical arm of which

elbow-lever in each truck is connected to the pull-rods D D' running longitudinally under the car, so that when these rods are drawn the 55 elbow-levers are turned, the cross-bar E forced down, and the two slides b and their brake-shoes carried down, and the latter forced into contact with the rails to stop the car. To lift the brake-shoes from contact with the rails flat 60 springs F are fastened to the main cross-bars of the truck, just above the cross-bars E, and are attached to the latter at their ends, so as to raise the cross-bars and the attached slides and brake-shoes whenever the pressure is relieved. 65

For exerting the pull upon the rods D D', I may use any known mechanical devices. I have devised a construction for this purpose, however, which I consider specially desirable. 70 The pull-rods are attached to the opposite ends of a horizontal lever, G, which is fulcrumed about its middle in a bracket, H, attached to the bottom of the car, the bracket being slotted where it receives the fulcrum-pin of the said lever, so that the pull upon both rods D and D' shall be equal and a uniform pressure transmitted to the two trucks of the car. 75

To one end of the lever G is attached a link-rod, e, whose other end is connected to a yoke-frame, f. Within this yoke-frame is contained a cylindrical or other form of bellows, I, working horizontally and longitudinally with the car. One of the heads of the bellows g is flanged and secured to the bottom of the car, and is 85 perforated also, to receive and form guides for the rods of the yoke-frame f. The other head, h, of the bellows is provided with ears that are rigidly attached to the yoke-frame, while the ends of the latter project through and are 90 guided by a plate, i, attached to the bottom of the car. The body of the bellows is made of leather or other suitable material. Opening into the interior of this bellows through the stationary head is a pipe, J, having a flexible 95 connection, K, coupling onto a pipe running to the engine, and connecting with a compressed-air cylinder, so that when compressed air is admitted the bellows is lengthened out and the brakes applied. 100

Instead of applying the brakes by compressed air, the apparatus may be reversed, so as to secure the same result by an exhaustion of air from the bellows.

In making use of the bellows as thus described, also, I do not confine myself to its use in connection with the particular form of brake described; but I may employ it to apply any 5 form of brake.

With respect to the mechanism for applying the brakes to the rail, I would state that I am aware that brake-blocks have been arranged to slide vertically in guides in the plane of the 10 two wheels of a truck, and that these brake-blocks have been connected in pairs by a bar running crosswise the track, near their lower ends, which bar is forced downwardly to apply the brakes by a pair of toggle-arms above 15 it. My construction differs from this, in that the brake-shoes have sliding stems *b*, which are connected at their tops by the bar *E*, and between which bar *E* and the truck-bar *B* a flat spring, *F*, is placed, while an elbow-lever, 20 *C*, is used for depressing bar *E*. This construction removes the brake mechanism as far as possible above the level of the track and keeps it out of the way of snow and other ob-

struction. I am also aware that a bellows has heretofore been used to apply the brakes, and 25 do not claim this broadly.

Having thus described my invention, what I claim as new is—

1. The combination of the brake-shoes *c*, having vertical sliding stems *b*, the vertical guides 30 *a a*, the cross-bar *E*, connected to the tops of the stems of the two brake-shoes of each truck, the truck-bar *B*, the spring *F*, interposed between bars *E* and *B*, and the elbow-lever *C*, substantially as and for the purpose described. 35

2. The combination of the lever *G* and the brake mechanism, the rod *e*, the bellows *J*, having fixed head *g*, with guide-holes, the yoke-frame *f*, passing through said guide-holes, and the movable head *h* of the bellows, attached to 40 the yoke-frame *f*, substantially as and for the purpose described.

WILLIAM LATTA CHAMBERS.
